The ornamental design for a lightweight socket structure, as shown and described.

DESCRIPTION

FIG. 1 is a perspective view of a lightweight socket structure showing my new design;

FIG. 2 is a top view thereof;

FIG. 3 is a bottom view thereof;

FIG. 4 is a front view thereof;

FIG. 5 is a left view thereof;

FIG. 6 is a rear view thereof; and,

FIG. 7 is a right view thereof.
